C. O. NORMAN.
DUST AND SILENCER HOOD FOR VALVE-IN-HEAD MOTORS.
APPLICATION FILED NOV. 24, 1917.

1,268,047.

Patented May 28, 1918.

29 Inventor:
Charles O. Norman
by G. J. Bell
Atty.

UNITED STATES PATENT OFFICE.

CHARLES O. NORMAN, OF MONTGOMERY, ALABAMA.

DUST AND SILENCER HOOD FOR VALVE-IN-HEAD MOTORS.

1,268,047.

Specification of Letters Patent. Patented May 28, 1918.

Application filed November 24, 1917. Serial No. 203,855.

To all whom it may concern:

Be it known that I, CHARLES O. NORMAN, a citizen of the United States, residing at Montgomery, in the county of Montgomery and State of Alabama, have invented certain new and useful Improvements in Dust and Silencer Hoods for Valve-in-Head Motors, of which the following is a specification.

10 This invention relates to accessories for internal combustion engines, and pertains especially to an attachment for protecting and silencing valve-in-head motors.

15 The object of the invention is to provide internal combustion engines, or valve-in-head motors such as are commonly used for driving automobiles, with an exterior attachment forming a hood or enclosure for certain operating mechanism, and affording 20 protection of such mechanism against dust and all other foreign matter, and also affording expeditious facilities for lubrication, and for muffling the noise of the engine.

25 A further object of the invention is to provide a support for the hood or cover which shall constitute the bottom closure or base of the hood or cover, and which shall support and connect the hood or cover 30 with the engine.

35 A still further object of the invention is to provide a hood support of such construction as to afford means for attaching the cover thereto, and as to afford means for holding push rod tubes or casings depending therefrom with the upper end of the tubes within the hood.

40 A still further object of the invention is to provide a cover or hood having a plurality of oil cups in the top thereof which shall register with a plurality of push rod casings having their upper ends within the hood, and a hood support forming the bottom of the hood and having said casings extending therethrough for centralizing the casings in the hood with respect to all cups attached to the hood.

45 Various other objects, advantages and improved results are attainable in the practical application of the invention as will be hereinafter fully set forth.

In the accompanying drawings forming part of this application:—

Figure 1 is a perspective view showing

the application of the invention as to a 55 valve-in-head engine.

Fig. 2 is a cross section as in applied position, showing one of the push rod casings partly broken away.

Fig. 3 is a top view of the supporting 60 base.

Fig. 4 is a detail perspective view showing a modification.

Fig. 5 is a similar view showing a further modification.

65 The same reference characters denote the same parts throughout the several views of the drawings.

70 My invention being specially applicable to internal combustion engines having overhead valves and exposed push rods, so much of such an engine is shown in the drawings as to illustrate the application of the invention, but the invention may be shaped and fitted to any engine having said parts 75 exposed.

75 In carrying out my invention I employ sheet metal of such weight and thickness as to readily admit of stamping into the desired shape for forming the hood or cover 80 1, and the base or support 2, for the hood.

85 The hood or cover 1, substantially comprises a top member 3, parallel side members 4 and 5 and end members 6 which are cut out or shaped at 7 to fit over two side end corners of an engine such as 8. The bottom edge of the side member 5 rests upon the top of the engine so as to elevate the top of the hood above the engine and thereby form a space for the engine valves such 90 as 9. The side member 4 extends below as 9. The side member 4 extends below and is off-set from the side member 5, so as to form a space for the upper end of the push rods 10, and their casings. Part of 95 one side of the hood is open by reason of this side 5 being shorter or of less depth than the opposite side 4, but said open portion is closed by the side of the motor or engine when the hood is applied thereto, with the hood ends fitting over opposite 100 ends of the motor, so that a portion of said side of the engine and the valve portion of the top of the motor are covered by the hood. The hood is provided with braces, preferably metal straps 11, riveted at 11^a to 105 the inner face of the hood, and said straps have a projecting end forming a tongue 12, the purpose of which will be hereinafter ex-

2
plained. The end members of the hood are inclined outwardly from the side member 4 to the side member 5 so as to produce flaring corners 1^a at each end of the hood, whereby 5 the hood is made to conform with the devices or parts to be housed by the hood.

For the purpose of supporting and connecting the hood with the engine, and for the purpose of closing the bottom of the 10 hood, I have devised a special device which is an important feature of my invention. Said device comprises preferably a stamped out metal plate 13 forming a support for and closing the bottom of the hood. The 15 plate has depending side flanges 14 through which bolts 15 extend for securing the supporting base to the engine, and the inner edge of the plate is curved at 13^a adjacent to each end so as to fit around two end corners 20 of the engine for supporting the end members 6 of the hood. The bottom edge of the side member 4 of the hood rests upon the supporting plate 13, which has slots 16 for the strap projections or tongues 12. The 25 plate 13 is provided with suitable apertures 17 for clamping bolts 18 and an opening 19 for the ignition wire. The bolts 18 extend through the plate 13 and preferably through straps of the hood for securely clamping 30 the hood to the supporting base. A plurality of holes 20 are made in the plate adjacent the inner edge thereof, and these holes are provided with annular flanges 21, which hold the upper end of the push rod tubes or 35 casings 22. The casings or tubes extend through the holes 20 and have their upper end within the hood 1. The lower end of the tubes 22 is enlarged and is provided with a shoulder 23 and a neck 24. The top 40 of the hood is provided with oil cups 25, one cup for each push rod 26, so that lubrication may be expeditiously perfected without removing the hood.

Referring to Fig. 4, the hood straps 28 shown therein are provided with screw ends 29 adapted to extend through the supporting base and to have suitable nuts for clamping the hood to the base.

Fig. 5 shows a further modification of 50 means for connecting the hood with the supporting base, by forming or stamping flexible tongues 30 in the bottom edge of the side 31 of the hood 32. Said tongues adapted to be passed through slots in the 55 supporting base and to be bent upon the inner face of the base. Obviously in using either of the modifications the clamping bolts hereinbefore described are not necessary, and the straps may be dispensed with 60 in using the modification shown in Fig. 5.

It will be seen that the hood as applied to 65 valve-in-head motors completely incloses such valves and the upper portion of the push rod casings so as to fully protect them from dust and other foreign matter injurious to the

same; that such inclosure muffles or silences the noise of the motor under working condition; and that, by reason of the location of the oil cups lubrication is protected and facilitated.

It will also be seen that the invention is exceedingly simple in construction and application, and that the parts thereof may be expeditiously assembled.

I do not wish to be understood as confining my invention to any particular size or material, nor do I wish to limit myself in the application of the invention to any particular capacity of the hood, or to the number of push rod casings held by the supporting base of the hood, neither do I wish to confine myself to any particular means for attaching the supporting base to a motor, but reserve the right to make such changes and variations in the manufacture and practical application of the invention and the parts thereof, as may be considered within the scope of the appended claims.

Having thus described my invention what I claim as new and desire to secure by Letters Patent is:—

1. A hood for valve-in-head motors, comprising a longitudinal side member for engaging the top of the motor, a longitudinal side member off-set from and depending below the other side member, a top member connecting the side members, end members having a cut out portion fitting a corner of the motor, a base extending laterally from the side of the motor for closing the bottom of the hood, and means for attaching the depending side of the hood to the base.

2. The combination with a one-piece hood for valve-in-head motors, and a hood supporting base having slots, of straps attached to the hood and having tongues projecting from the hood for engaging the slots.

3. The combination with a hood for valve-in-head motors, and a hood-supporting base having slots, of straps attached to the hood and having one end depending from one side of the hood and forming tongues for engaging the slots.

4. The combination with a hood for valve-in-head motors, and a hood-supporting base adapted to fit one side of the motor and having slots, of tongues depending from one side of the hood and extending through the slots.

5. The combination with a hood for valve-in-head motors, and a hood-supporting base adapted to fit one side of the motor and having slots, of tongues depending from one side of the hood and extending through the slots, clamping bolts for securing the hood to the base, and bolts for securing the base to the motor.

6. The combination with a hood for valve-in-head motors, a hood-supporting

base attached to the motor, a plurality of push rod casings extending through the base and projecting into the hood, and oil cups secured to the top of the hood opposite the upper end of the casings.

7. The combination with a hood for valve-in-head motors adapted to have one side member supported by the top of the motor, and a portion of this side thereof 10 closed by application to the motor, and inclined hood ends having a cut out, of a supporting bottom fitting the said closing side

of the motor and having the other side of the hood resting thereon, a plurality of push rod casings held by said bottom and projecting into the hood, means for connecting the hood with the bottom, and means for connecting the bottom with the motor. 15

In witness whereof I hereunto set my hand in the presence of two witnesses.

CHARLES O. NORMAN.
